UNITED STATES PATENT OFFICE

155,415

DESIGN FOR A GAME BOARD OR SIMILAR ARTICLE

Melvin S. Goodick, Somerville, Mass.

Application August 21, 1947, Serial No. 140,986

Term of patent 14 years

(Cl. D34—5)

To all whom it may concern:

Be it known that I, Melvin S. Goodick, a citizen of the Dominion of Canada, residing at Somerville, in the county of Middlesex in the Commonwealth of Massachusetts, have invented a new, original, and ornamental Design for a Game Board or Similar Article, of which the following is a specification, reference being had to the accompanying drawing, forming a part thereof, in which the figure is a top plan view of a game board or similar article, showing my new design. The design on the drawing shows surface representations, and the game board is of conventional thickness.

I claim:

The ornamental design for a game board or similar article, substantially as shown and described.

MELVIN S. GOODICK.
